UNITED STATES PATENT OFFICE.

JAMES ALFRED KEAY, OF LEICESTER, ENGLAND, ASSIGNOR TO UNITED SHOE MACHINERY COMPANY, OF PATERSON, NEW JERSEY, A CORPORATION OF NEW JERSEY.

APPARATUS FOR USE IN THE MANUFACTURE OF BOOTS AND SHOES.

1,135,024.

Specification of Letters Patent.

Patented Apr. 13, 1915.

Application filed July 18, 1912. Serial No. 709,714.

To all whom it may concern:

Be it known that I, JAMES ALFRED KEAY, a subject of the King of Great Britain, residing at Leicester, Leicestershire, England, have invented certain Improvements in Apparatus for Use in the Manufacture of Boots and Shoes, of which the following description, in connection with the accompanying drawings, is a specification, like reference characters on the drawings indicating like parts in the several figures.

This invention relates to apparatus for softening the toes or other portions of boots or shoes by the use of steam or vapor.

In connection with the lasting of shoes, it has been found advantageous to soften the toe box and the upper, particularly of heavy work and of high toed shoes, in order to render it more pliable and thus to facilitate the molding of the upper over the toe of the last and the plaiting of the stock over the insole. Apparatus for treating shoes in this manner, as heretofore proposed, however, have usually been so constructed that they start into operation very slowly and they usually have been dependent upon an external supply of steam, thus rendering their installation comparatively expensive and limiting their use to factories equipped with a steam supply system.

It is an important object of this invention to produce an apparatus of this character which shall be self-contained, and which shall be capable of starting into operation without delay.

It is a further object of the invention to provide means by which the regulation of the quantity of steam can be readily effected and to produce an apparatus that can be economically manufactured.

The particular manner in which these and other objects of the invention are attained will be clearly understood from the following description of one embodiment thereof, reference being made to the accompanying drawings, in which—

Figure 1 is a view in front elevation of a toe softening apparatus; and Fig. 2 is a view in side elevation of the apparatus, certain parts being shown in section.

The apparatus shown comprises a hollow base 2 and a casing 4 bolted thereon, having in its front wall two apertures 6 each shaped to receive the toe portion of a shoe.

The top of the casing slopes upwardly from its opposite ends to points substantially over the positions occupied by the shoes in the apparatus and from these points it slopes downwardly to the middle of the casing. This arrangement provides in the top of the casing two raised portions and a central depressed portion. At the lowest point of the latter portion an orifice 8 is formed through the casing. Upon each of the raised portions there is a pedestal 10 which supports a receptacle 12 for water, and a cock 14, threaded into the bottom of the receptacle, is positioned directly over the orifice 8 so that, when the cock is opened, it will release water from the receptacle and direct it through the orifice 8 into the casing 4.

Between the base 2 and the casing 4 there is supported a thin metal diaphragm 16 which preferably is concaved or dished so that the water dropping through the orifice 8 will strike it and gravitate toward its center. A burner 18 of any suitable type is fixed in the base 2 directly below the diaphragm 16 and serves to heat this member, the central portion of the diaphragm being corrugated in order to increase its heat radiating capacity. The products of combustion may escape through an aperture 20 at the back of the base. In front of the base an opening 22 is provided through which the burner 18 may be lighted. This opening may be partially closed by a cylindrical shutter 24 which is slidably mounted in the upper part of the base upon lugs 26 that project inwardly from the walls of the base. The shutter has an aperture formed therethrough and has a handle 28 projecting through the opening 22 by means of which it may be moved to cause this aperture to register with the opening 22 to permit the lighting of the burner or to close the opening again after the burner is lighted. In order to permit the shutter to be mounted in the manner shown, a slot is cut in the front wall of the base from its upper edge to the opening 22, as indicated at 30 in Fig. 1.

The shoes are supported with their toes projecting through the apertures 6 into the casing 4 by means of adjustable rests 32 which may be of any suitable or convenient form, and by a guard plate 34 of wood or

- other heat insulating material that is clamped between the rests and the casing 4 and has semicircular notches cut in its upper edge to receive the toes of the shoes. 5 These notches register with the apertures 6 but their edges overlie the edges of the apertures and therefore prevent the shoe from coming into contact with the metal of the casing. As a further protection for the shoe, 10 a strip 36 of wood or other heat insulating material is supported inside the casing substantially on a level with the toes of the shoes to prevent the shoe from striking the back of the casing.
- 15 In using the apparatus, the cock 14 is opened slightly allowing the water to flow from the receptacle drop by drop through the orifice in the top of the casing on to the heated diaphragm where it is immediately 20 evaporated. By adjusting the cock 14 the rate at which the water will be supplied to the diaphragm can be regulated and, consequently, the rate at which the steam will be generated can be easily controlled. Furthermore, 25 since the quantity of water to be heated in a given time is relatively small, only a moment's time is required to start the apparatus into full operation. The steam rises in the casing around the toes of the 30 shoes, penetrating the leather and making the stock soft and pliable. The peculiar shape of the top of the casing is of advantage since by this arrangement substantially all of the vapor that condenses on the walls 35 of the casing will be conducted either to the central part adjacent to the orifice 8, or else to the sides of the casing where it will flow to the diaphragm 16. In other words, this 40 condensed vapor will be conducted away from the positions where it would be likely to drop on to the inner sole.
- Having thus described my invention, what I claim as new and desire to secure by Letters Patent of the United States is:—
- 45 1. An apparatus of the character described comprising a casing, means for supporting a shoe with a part thereof in said casing, a base supporting said casing, a burner in said base, a diaphragm positioned 50 over said burner, said base having an open-
- ing in one side thereof, and a sliding shutter for said opening.
2. An apparatus of the character described comprising a casing having two apertures in one wall thereof, means for supporting two shoes with their toe portions in said apertures, the top of said casing being inclined upwardly from its ends to points substantially over the positions occupied by the shoes and thence sloping downwardly to the middle of the casing, and means for generating vapor in said casing. 60
3. In apparatus of the character described comprising a casing, means for supporting a shoe with a part thereof in said casing, a base for said casing, means for supplying vapor to said casing comprising a burner positioned in said base, said base having an opening in one side thereof, and a shutter for said opening. 70
4. An apparatus of the character described comprising a casing, means for supporting a shoe with a part thereof in said casing, means for supplying a series of small quantities of water to said casing, and means for vaporizing the water substantially as fast as it is supplied to the casing. 75
5. An apparatus of the character described comprising a base, a casing supported thereon, a receptacle for water mounted on said casing, a diaphragm positioned between said casing and base, said casing having an orifice in its top directly over said diaphragm, a cock positioned over said opening to control the flow of water from the receptacle, a burner in said base for heating said diaphragm, said base having an opening in one side thereof, and a cylindrical shutter slidably mounted in said base having an opening therein which may be moved 85 into or out of register with the opening in the base. 90

In testimony whereof I have signed my name to this specification in the presence of two subscribing witnesses.

JAMES ALFRED KEAY.
